SUPPORT TRAY FOR FOOD PROCESSING MACHINE

Clyde E. Schul, Wildcat Township, Elk County, Kans., assignor to Marc Mfg., Inc., Wichita, Kans., a corporation of Kansas

Filed Apr. 23, 1969, Ser. No. 16,855

Term of patent 14 years

Int. Cl. D15—12; D7—02
U.S. Cl. D55—1

FIG. 1

FIG. 2

FIG. 4

FIG. 1 is an isometric view of a support tray for food processing machine showing my new design, with an environment of use of my design being indicated in dashed lines;

FIG. 2 is a greatly enlarged side elevational view thereof.

FIG. 3 is an enlarged bottom view thereof;

FIG. 4 is a vertical sectional view thereof, such view being taken upon the plane of the section line 4—4 in FIG. 3.

I claim:

The ornamental design for a support tray for food processing machine, substantially as shown and described.
